UNITED STATES PATENT OFFICE.

PERCY I. ANSORGE, OF BROOKLYN, NEW YORK.

DESIGN FOR A LIGHTING-FIXTURE BODY.

Application filed October 15, 1926. Serial No. 19,362. Term of patent 7 years.

To all whom it may concern:

Be it known that I, PERCY I. ANSORGE, a citizen of the United States, residing at 319 St. Johns Place, in the county of Kings, borough of Brooklyn, and city and State of New York, have invented a new, original, and ornamental Design for a Lighting-Fixture Body, of which the following is a specification, reference being had to the accompanying drawing, forming part thereof.

Figure 1 is a front view of a lighting fixture body, showing the outline of my new design, with only a portion of the ornamental

portion completed, it being understood that the unornamented portion involves a mere repeat of the part more fully illustrated.

Figure 2 is a diagrammatic side view of a lighting fixture body for the purpose of showing the contour of the article illustrated in Figure 1.

I claim:

The ornamental design for a lighting-fixture body substantially as shown and described.

PERCY I. ANSORGE.
